CLAIM

We claim the ornamental design for an adhesive bandage with decorated pad, as shown and described.

DESCRIPTION

FIG. 1 is a top perspective view of the present invention; FIG. 2 is a top view of the adhesive bandage with decorated pad depicted in FIG. 1; FIG. 3 is a left side view of the adhesive bandage with decorated pad depicted in FIG. 1; FIG. 4 is a bottom view of the adhesive bandage with decorated pad depicted in FIG. 1; FIG. 5 is a right side view of the adhesive bandage with decorated pad depicted in FIG. 1; FIG. 6 is a front side view of the adhesive bandage with decorated pad depicted in FIG. 1; and, FIG. 7 is a back side view of the adhesive bandage with decorated pad depicted in FIG. 1.
